Application May 31, 1949, Serial No. 86,296

10 Claims. (Cl. 53—25)

1

This invention relates to machines for forming package envelopes from sheet material.

An object of the invention is to provide a machine, capable of operation at a comparatively high rate of speed, for forming and separating individual hermetically sealed packages from continuous supply strips of sheet material.

Another object of the invention is to provide a machine of the character described in which one of a pair of strips of material, from which individual packages will be subsequently formed and separated, serves as conveying means for receiving and transporting articles to be packaged in proper order to and through the mechanisms which form and separate the packages from the parent strip material.

A further object of the invention is to provide, in a machine of the class described, improved strip feeding control mechanism which insures that individual packing-forming components of the parent sheet material are properly positioned and brought to a complete stop relative to the mechanism for separating the formed packages from the parent strip before said separating mechanism may function.

Still another object of the invention is to provide, in a machine of the character referred to as having positive drive mechanism for linearly advancing a strip of sheet material, means timed with the linear movement of the strip for instantly stopping the latter without perceptible overrun at uniformly spaced points relative to the linear dimension of the strip.

A still further object of the invention is to provide, in apparatus of the type referred to, novel means for synchronizing independently driven strip feed and cut-off mechanisms so that cuts will be made in the strip material in proper relation to individual packages formed therein irrespective of disparities in the relative normal operational speeds of the strip-feeding and cut-off mechanisms.

It is another object of the invention to provide novel means, in a machine of the class described including a selectively engageable and releasable clutch mechanism, which is sensitive and capable of rapid operation in actuating the control element of such a clutch mechanism.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description

2

may be adopted within the scope of the invention as set forth in the claims.

Referring to the drawings:

Figure 1 is a portional top plan view of the package forming and sealing machine of my invention, a section of the loading table being broken away so as to conserve space in the drawing.

Figure 2 is a reduced scale side elevational view of the complete machine of my invention.

Figure 3 is an enlarged scale vertical sectional view taken in the plane indicated by the line 3—3 of Figure 1.

Figure 3A is a view similar to Figure 3 showing the mechanism parts in intermediate positions of their operative cycles.

Figure 3B is a view, equivalent to Figure 3A showing further positions of the mechanism parts in their operative cycles.

Figure 4 is an enlarged scale side elevational view of a portion of the machine viewed in the plane indicated by the line 4—4 of Figure 1.

Figure 5 is an enlarged scale vertical sectional view taken in the plane indicated by the line 5—5 of Figure 1.

In carrying out our invention, we provide a suitable supporting structure here shown in Figure 2 as comprising a structural steel base plate or frame 6 attached to and rising from which is a plurality of support legs 7 interconnected by suitable tie bars 8 and braces 9 to impart proper rigidity to the group of support legs. Connected to a portion of the vertically extending support frame, preferably the upper ends of the legs 7, is a horizontally extended table structure here shown as comprising a pair of parallel side rails 10, formed of suitable structural bars, which are joined at end and intermediate portions by laterally extending cross members 11 superposed on which is a plate 12 or its equivalent which provides a table surface extending along the major portion of the length of the side rails 10 and terminating short of one end cross member 11 to provide an enlarged opening, generally indicated by the numerals 13 of Figure 1, which extends vertically through what will hereinafter be referred to as the discharge end of the table, the opposite end and adjacent portions of the table being hereinafter referred to as the loading end.

At a point substantially medially of the length of the table, and also at a point closely adjacent to the extreme outer loading end thereof, is provided a pair of relatively spaced supports here shown as each comprising vertically-extending

side frames, which may conveniently consist of axially vertical posts 14, secured at their bottom ends to the side rails 10, having horizontal header bars 16 attached in any suitable manner to their upper ends and arranged in spaced parallel relationship laterally of the table. Each of the header bars 16 serves as the elevated foundation for one of laterally opposed pairs of bearings each comprising relatively superposed base and cap sections 17 and 18 respectively joined at one end by a pivot pin 19 and at the opposite end by a stud 21 carried by the base section 17, extending upwardly through a suitable clearance opening provided in the cap section 18 and threadedly engaged with a wing nut 22 or its equivalent which overlies and engages the cap section. A journal bore 23, whose horizontal axis lies preferably in the separation plane 24 between the base and cap sections of the bearing, is provided in each bearing and is axially aligned with the similar bore 20 of the companion bearing which is disposed laterally of the machine table. In the journal bores 23 of each related pair of bearings are disposed the opposite ends of axially horizontal shafts 26 which serve as axle supports for supply rolls 27 of strip package-forming material, the strip 28 from the outermost supply roll being threaded under a suitable guide roller 29, as shown in Figure 2, and thereafter passed along the table to subsequently form the bottom closure sheet for the package as will be later explained, while the strip 31 from the other supply roll is threaded under a similar guide roller 32 and is passed along the table in superposed relation to the strip 28 to subsequently form the upper closure sheet for the package. The split bearing type of support for the supply roll shafts is provided so that replacement rolls of strip material may be rapidly mounted and may also function, if desired, as braking means so that by setting of the wing nuts 22 a frictional pressure of the bearing sections on the shafts may be secured which will offer resistance to rotation of the shafts and their associated supply rolls as the strips 28 and 31 are moved along the table thus insuring that a desirable degree of tautness is maintained in the strips at all times. Of course, in order to secure this operation, it will be necessary to fix the supply rolls to their supporting shafts 26, one way of effecting this being shown in Figure 1 wherein the collars 33 carried by the shafts are clamped in tight engagement with the innermost radial side areas of the supply rolls or with the ends of the spools 34 forming the core members of the supply rolls. By referring to Figure 2 it will be seen that the strip 28 passes for a considerable distance along the table between the respective supply roll supports and it is in this area of the table that the operation of loading of the articles 36 to be packaged on the moving bottom strip 28 is performed, by the latter strip, as clearly shown in Figure 1, being provided along one edge with preferably opaque imprint marks 37 spaced apart a distance equivalent to the desired side dimension of the finished package and defining transverse bounding planes of the successive strip areas in each of which an article 36 to be packaged is manually placed and centralized by the machine operator. Thus the bottom strip serves as a conveyor for carrying the articles 36 in prearranged and uniformly spaced order toward and under the guide roller 32 of the supply roll dispensing the upper strip wherat the latter strip overlies the articles to be packaged and may

be subsequently sealed to the bottom strip to enclose the articles in their packages.

The sheet material employed for the strips 28 and 31 is preferably a resinoid film commonly referred to as cellophane, the so-called waterproof or surface coated variety of the latter being most desirable. However any material which is impregnated or coated with substances capable of adhering or fusing under applications of heat and/or pressure, so as to hold with a high degree of tenacity, may be used as well. Such materials may comprise, for instance, heavily waxed or latex-coated papers. The most desirable material however is the cellophane due to its transparency, so that the packaged product may be shown to best advantage, to its ready acceptability of printing inks for package decoration and the like and to the rapid fusibility of its surface coating which under comparatively low heat and pressure is capable of bonding securely with the surface coating of another intimately engaged sheet to form a very tight impervious seal for the resulting package.

Means are provided for moving the bottom sheet 28, the articles 36 to be packaged borne thereby, and the superposed top sheet 31, in unison along the table and for progressively sealing edge portions of the respective sheets together during such movement. Mounted on and rising from the table at opposite ends of the side of the discharge opening 13 closest to the loading end of the table is a pair of relatively spaced perpendicular support members 38 in which are journaled rocker shafts 39 and rotatable drive shafts 41 arranged in vertically spaced pairs above and below the plane of the engaged strips 28 and 31 and extending, axially, transversely thereacross. At intermediate points in the length of each rocker shaft 39 is secured, by pins 42 or the like, a horizontally spaced pair of radially extending arms 43 in the distal ends of which is journaled a roll shaft 44 and in intermediate portions of which is similarly journaled an idler shaft 46, all of the shafts 39, 41, 44 and 46 being in parallel relation with each other. Each of the roll shafts 44 is provided at opposite ends thereof with circular sealing rolls 47 having internal recesses 48 opening at the outer faces of the rolls and bordered by rims 49 which have their outer peripheries provided with preferably groove knurling 51. In each of the sealing roll recesses 48 is disposed a disk-shaped electric heater unit 52 which is free of the shaft 44 and the roll 47, so that the heater unit may remain stationary as the shaft and roll rotate, and which is provided with current-supply conductors 53 connected with a source of current for energization of the heater units so that heat radiated from the latter will maintain the sealing roll 47 and particularly the rim portion 49 thereof at a desired temperature. Means are provided for driving at least one set of the sealing rolls so as to effect rotation thereof. As here shown, each of the roll shafts 44 has a gear 54 secured thereto which meshes with a primary idler gear 56 secured to and rotatable with the idler shaft 46, the latter gear being in mesh with a secondary idler gear 57 freely journaled on the rocker shaft 39 and meshing with a drive gear 58 secured to and rotatable with the drive shaft 41. It will be thus seen that rotation of the drive shaft 41 will be imparted to the roll shaft 44 by the gear train just described. Secured to corresponding ends of the rocker shafts 39 are intermeshed quadrant gears 59 one of which has an

operating lever 61 extending radially upwardly therefrom whose function is to provide a timed rotational movement of the quadrant gears 59 and a corresponding rocking movement of the shafts 39, by mechanism to be subsequently described, so that the respective pairs of sealing rolls 47 will be caused to approach and recede from the plane of the engaged strips 28 and 31. With the sealing rolls in rotational motion, relative radial approach thereof will cause the strips 28 and 31 to be clamped between the knurled peripheries 51 thereby causing the marginal side portions of the strips to be crimped into intimate contact with each other and as a result of such crimping to be effectively meshed with the rolls so that continued rotational movement of the latter will serve to draw the strips, and the articles to be packaged carried by the bottom strip 28, longitudinally along the table. Of course, during such operation, the heated rolls will effect softening of the surface coating of the sheets and consequently the sheets, in the marginal areas thereof, engaged by the rolls, will be fused into intimate permanent engagement. It will be seen that as long as the sealing rolls are in clamping engagement with the strips 28 and 31 the aforesaid movement of the sheets will continue, the said movement being capable of being instantly interrupted at any time by the action of causing the upper and lower pairs of sealing rolls to move relatively radially apart so that clamping engagement of the rolls with the sheets is released.

One or both of the shafts 41 may be power driven, the latter arrangement being preferred. As here shown in Figure 3 each of the shafts 41 has a worm pinion 62 secured to and rotatable therewith each of the latter gears being in mesh with a worm 63 carried by a shaft 64 which is journaled in suitable bearings 66, formed on the downward extension of one of the support members 38 journaling the shafts 39 and 41, and which has attached to the outer end thereof a preferably peripherally grooved pulley 67 tractionsally engaging a loop belt 68 likewise engaged with a pulley 69 mounted on the drive shaft 71 of a motor 72 suitably attached by a mounting bracket 73 or the like to a side rail of the table or to any convenient portion of the supporting frame thereof. By this gearing arrangement it will be seen that the sealing rolls 47 may be rotated, upon energization of the motor 72 in relatively counter directions and in synchronism so that when the sealing rolls are moved radially together into substantial peripheral engagement the package strips 28 and 31 and the articles 36 carried by the bottom strip 28 will be caused to move along the table at a linear speed corresponding to the peripheral velocity of the rotating sealing rolls. It will also be seen that the moment tractional grip of the rolls on the sheets is ceased by movement apart of the rolls, the linear motion of the package sheets will be instantly halted regardless of whether or not the sealing rolls continue to rotate. The particular worm gearing drive herein shown was chosen with a view toward simplification of the drawings but it will be apparent to those skilled in the art that the same end result may be obtained in a number of different ways. For instance, only one of the shafts 41 need be driven through a worm and gear from the motor 72, the gears 57 being then interconnected by a suitable pair of idler gears. In fact it is also possible to drive only one of the pairs of upper or lower sealing

rolls since the intermeshing of the peripheral grooves of the rolls, when the latter are in engagement to pinch the package sheets therebetween, is fully sufficient to impart rotation from one sealing roll to the other and thus effect linear movement of the package strips.

Means are provided for causing the upper and lower sealing rolls to intermittently approach and recede from each other so as to effect linear movement of the package sheets along the table in measured increments. Journaled in suitable bearings 74 provided at the upper ends of the support members 38 is an axially horizontal cam-shaft 76, extending transversely across and above the table, on one end of which is journaled a flywheel 77 preferably peripherally grooved to tractionsally engage one or more endless drive belts 78 which are similarly engaged with a drive pulley 79 carried by the shaft 81 of a main drive motor 82 attached to a base bracket 83 suitably mounted on an end portion of the table supporting frame. On the shaft 76 is fixedly mounted a throw-out cam 84 engageable and cooperative with a roller 86 journaled on an axially horizontal pin 87 secured to the outer end of the operating lever 61 which, as was previously explained, is fixed to one of the rocker shafts 39. Although the motor 82 operates continuously to rotate the flywheel 77, the cam-shaft is capable of controlled intermittent rotation. This is accomplished by interposing suitable selectively engageable and releasable clutching means between the flywheel and cam-shaft which clutching means may conveniently comprise the type employed in conventional punch press drives wherein a sleeve 88 forming one element of the clutch mechanism is fixed to and is capable of rotation with the cam-shaft 76 while the flywheel 77 which is freely journaled on the sleeve forms the other element of the clutch mechanism. A sliding or rocking key carried by the sleeve is reciprocable to relatively engage or disengage the clutch elements so as to connect the flywheel to and for rotation with the cam-shaft or to effect disengagement thereof this being accomplished by operation of a radially extending trip finger 89 which is attached to and is movable with the above mentioned sliding or rocking key. Normally, the key is held in engagement by spring pressure, as is well known in the art, so that the elements of the clutch are relatively engaged to connect the flywheel and cam-shaft together for rotation in unison, such engagement of the clutch key being accompanied by movement of the trip finger 89 to a position adjacent to the end of the sleeve 88. During the ensuing rotation of the flywheel and sleeve the trip finger will rotate with the latter. Disengaging of the clutch may be effected by a release lever 91, shown in Figure 3, which is mounted adjacent its lower end on a pivot pin 92 carried by one of the support members 38 and whose wedge-shaped upper end portion 93 may be moved into and out of the path of rotation of the trip finger 89. If, during engagement of the clutch, the end of the release lever should be moved into said path, the trip finger will engage the intruding end and will be forced thereby to move away from the sleeve 88 so as to withdraw the clutch key and disengage the flywheel from the sleeve. Such disengagement takes place instantaneously and brings the trip finger 89 back to its initial starting position. If the release lever 91 is subsequently swung outwardly away from the trip finger, the latter will again be released to engage

the clutch and to maintain such engagement for a single revolution of the flywheel and cam-shaft if in the interim the release lever is again returned to its inward position to engage and retract the rotating trip finger. Such limiting of the camshaft 76 to single intermittent rotational movements is utilized to assist step by step advancement of the strips 18 and 31 on the table this being accomplished by providing the cam 84 with separate peripheral portions 94 and 96 of lesser and greater radial curvature respectively the former portion 94, when in engagement with the operating lever roller 86, which engagement is maintained by a spring 97 interposed between the lever 61 and a mounting plate 98 secured to and extending from one of the support members 38, allowing the sealing rolls 47 to relatively approach each other so as to engage and move the package strips 18 and 31 along the table, while the latter portion 96, when rotated to engage the roller 86 effecting an outward swing of the operating lever 61 so as to relatively separate the sealing rolls and consequently stop the linear movement of the package sheets.

Manually actuatable means is provided for controlling the engagement of the sealing rolls so as to effect advancement of the package strips in successive increments. Extending along a side of the table in a position wherein it may be conveniently reached by an operator standing in front of the table loading space is a control 99 attached to the ends of which are radially-extending levers 101 secured to and rotatable with a rocker shaft 102 journaled at end and intermediate points in bearing brackets 103 attached to and extending from a side rail of the table. To one end of the shaft 102, as shown in Figure 4, is affixed a radially extending arm 104 having at its distal end a universal joint 106 connected to an upwardly directed rod 107 which is pivotally engaged at its upper end to the mid-pivot 108 of a pair of toggle links 109 attached, respectively, by pivot pins 111 to the operating lever 61 and to the mounting plate 98. The starting point of the cycline movement of the lever is indicated by the dotted lines of Figure 4 in which position the toggle links 109 will be in relative linear alignment. If at any time, when the sealing rolls 47 are not performing the operation of advancing the package sheets, the operator desires to institute such advancement, manual depression of the control rod 99 will cause the normally linearly aligned toggle links 109 to be brought into relative angular alignment thereby forcing the lever 61 to swing inwardly to move the roller 86 into the peripheral recess of the cam 84 and consequently to effect relative approach of the sealing rolls. In the cyclic operation of the lever 61 the spring 97 applies the sealing pressure between the co-acting rolls 47 the lever 61 being then returned by the cam 84 to its normal outer rest position. Except at the latter position of the lever 61 the toggle links 109 are always in some degree of angular relationship with one another so that the lever 61 may move freely but when the lever is in its outer position the links 109 being in relative alignment will lock the lever 61 in said outer position against the tendency of the spring to return the lever to its inner position, this lock being incapable of being released until the operator flips the control rod 99 downwardly to again institute advance movement of the package strips.

Means are provided operative during the in-

75 package strips is halted due to relative sepa-

tervals when the advancement of the package strips is interrupted for sealing the latter in transverse areas which are equally spaced longitudinally of the strips so as to enclose the articles 36 in individual hermetically sealed packages. Secured to and rising from the opposite side rails 10, at positions intermediate the sealing rolls 47 and the discharge opening 13 of the table, are vertically extending guide members 112 provided in the relatively confronting inner faces thereof with vertical guide channels 113 in which is slidable a sealing head 114 extending transversely of the package strips and provided in its bottom surface with serrations 116 adapted to intermesh, in the plane of movement of the package sheets, with complementary serrations 117 formed in the upper surface of a sealing bar 118 underlying and paralleling the sealing head 114 and fixedly secured at its opposite ends to the table side rails 10. The sealing head 114 and the sealing bar 118 are preferably each provided with embedded electric heater elements 119 by means of which heat sufficient to cause fusion of the surface coatings of the package strips may be generated and conductively transmitted to the respective serrations 116 and 117. Attached to and depending from the opposite side rails 10, at points below the fixed sealing bar 118, are bearing brackets 121 in which is journaled a shaft 122 extending transversely of and under the table and carrying, at its opposite ends, levers 123 which are pivotally engaged by pins 124 with the lower ends of links 126 similarly pivotally attached at their upper ends by pins 127 secured to and extending horizontally from opposite ends of the sealing head 114. To one end of the shaft 122 is also connected, by a suitable clamping bolt 128 the lower split end 40 of an upwardly extending lever 129 connected at its distal end, and by means of a pivot pin 131, with a link 132 whose opposite end is pivotally attached, by means of a pivot pin 133 with the lower end extension 134 of a control lever 136 which, in an intermediate portion, is rockably journaled on a pivot pin 137 secured to and extending from one of the support members 38 and which at its upper distal end is fitted with a pivot pin 138 on which is journaled a follower roller 139 adapted to bear against the peripheral surface of a cam 141 secured to and rotatable with the camshaft 76. A spring 142 secured at one end to the lever extension 134 and at its other end to an anchor pin 143, projecting outwardly from the adjacent side rail 10, serves to forcibly maintain the follower roller 139 in engagement with the periphery of the cam 141. The cam 141 is so shaped that, during each revolution thereof with the crankshaft 76, the lever 136 will be reciprocably rocked thus causing the sealing head 114 to rise and descend in its guide channels 113, in the former case to permit free movement of the package strips 28 and 31 thereunder and in the latter case to clamp the package strips between the intermeshed serrations 116 and 117 and thus cause fusion and relative adherence of transverse areas of the package strips enclosed between the sealing head and bar. The relative circumferential positions of the cams 84 and 141 is such that the sealing head will descend to engage the package strips only during the interval when the roller 86 is overlying the portion 96 of the cam 84 or when the longitudinal motion of the

ration of the sealing rolls 47. At a subsequent time when the sealing rolls are again brought together to grip the package strips, the sealing head 114 will have already started to rise after completing the transverse seal and consequently the package strips will be free to be moved longitudinally along the table.

As each transverse sealing of the package strips is being effected by the sealing head 114 and bar 118, separation of a completed package, along the transverse sealed area previously made, is being accomplished. This is effected by providing each inward and relatively confronting face of the support members 38 with vertically extending guide grooves 144, as shown in Figure 5, in which are vertically slidably disposed the opposite ends of a longitudinally horizontal shear bar 146 to the bottom portion of which is suitably attached, such as by means of mounting screws or bolts 147, a shear blade 148 having a sharpened lower cutting edge 149 disposed in vertical planar registry with a cooperative fixed shear element here shown as the edge surface 151 of the table 12 forming one side of the discharge opening 13. The upper edge of the shear bar 146, preferably in a portion thereof medially of its ends, is provided with a pair of relatively horizontally spaced and upwardly rising brackets 152 between which is disposed a roller 153 which is journaled on an axle 154 secured in the brackets 152 and which is adapted to be constantly peripherally engaged by a cam 156 secured to and rotatable with the camshaft 16. Such interengagement of the cam 156 and roller 153 may be effected in numerous ways and is here shown as being accomplished by one or more coil springs 157 interposed between a portion of the shear bar, preferably the upper end of a bracket 152 and one or more collars 159 freely journaled on the cam shaft 16. The arrangement of the parts and the circumferential position of the cam 156 relative to the cam 84 are such that as the roller 86, previously swung inwardly by the manual control means previously described, has just come into engagement with the surface 96 of the latter cam to relatively separate the sealing rolls 47, the point of greatest radial throw of the cam 156 will be coming into tangential engagement with the roller 153 thus causing the shear blade 148 to descend against the tension of the springs 157 to vertically traverse the fixed shear element or table edge 151 thereby shearing through the interposed package strips 29 and 31 substantially laterally medially of a transverse seal thereof and separating a finished package 161 therefrom, as shown in Figure 1, which package is then free to fall through the discharge opening 13 onto suitable receiving means which is here shown as a roller conveyor 152 along which the packages may thereafter move, preferably under the influence of gravity to an advanced collection or processing station not shown.

It will be seen that since the package-forming means, comprising the transverse sealing head 114 and the cut-off shear 148, and the strip-advancement mechanism comprising the sealing rolls 47 are driven independently by separate motors 82 and 72 respectively, it would be possible due to speed variations in the respective motors, that disturbance in proper timing between the intermittently successive operations might occur which might possibly cause variations in the sizes of respective packages and possible shearing of the package strips in areas

thereof other than those in which the transverse seals are located. Means is therefore provided for precisely regulating the degree of each advance of the package sheets along the table so that the aforesaid transverse sealing and cut-off will be accomplished in the proper places. As shown in Figure 3, a stanchion 163 is secured to and rises from the side rail 10 which borders the discharge opening 13, on the side thereof adjacent the flywheel 17, and is provided at its upper end with a horizontally extending plate 164. On the stanchion 163, at a point intermediate the upper and lower ends thereof, is provided a pivot pin 166 on which is journaled one end of a toggle link 167 pivotally connected at its other end, by means of a pivot pin 168, with a second toggle link 169 which, by means of a pin 171, is pivotally connected with the release lever 91. A spring 172 connected at one end with the second toggle link 169 and at the other end with an anchor pin 173 carried by the plate 164, is arranged to urge the connected toggle links 169 and 167 into relative longitudinal alignment and thereby retain the release lever 91 in position wherein it holds the trip finger 89 in retracted position and consequently maintains the flywheel clutch in released condition. Also carried by an upper portion of the stanchion 163 is a pivot pin 174 on which is mounted for vertical rocking movement a lever 176 having at the extreme distal end thereof a pivot pin 177, connected with the upper end of an elongated downwardly extending pull link 178, and also having in an intermediate portion thereof a pivot pin 179 to which is connected a depending wing member 181 pivotally engaged at its lower end, by means of a pin 182, with the upper end of a connecting link 183 which, in turn, is pivotally engaged, by means of a pin 184, with a medial portion of the toggle link 167. The laterally extending portion of the wing member 181 carries and journals a roller 186 which, during vertical movement of the wing member and its connected link 183, is engageable with the vertically inclined upper cam surface 187 of a fixed block 188 secured to a lower portion of the plate 164. The lower end of the pull link 178 is pivotally attached, by means of a pin 189, with the vertically reciprocable armature 191 of an electrically-energizable solenoid 192 which is mounted by means of a bracket 193, or other such means, on a side rail 10 or other convenient portion of the mechanism supporting structure. A coil spring 194, secured at one end to a portion of the lever 176 and at the other end to a wing extension 196 of the plate 164, exerts force to yieldably hold the lever 176 at the uppermost limit of its movement and consequently similarly retains the armature 191 in an extended elevated position as indicated in Figure 3. The coil spring 194 also retains the link and wing members 183 and 181 respectively in vertically aligned positions, relative to the axes of their pivot pins and also holds the toggle link 167 in an upward stopped position against the underside of the block 188 thereby maintaining the toggle links 167 and 169 in relative horizontally aligned positions so as to retain the release lever 91 in engagement with the trip finger 89 and preserve a released condition of the flywheel clutch. The spring 194 operates, in this instance, in conjunction with the spring 172 to yieldably retain the toggle links 167 and 169 in the aforesaid horizontally aligned position but is capable of independent action relative to the latter spring in effecting operation of the

trip mechanism as will be presently described. An additional spring 197 interposed between the wing member 181 and a portion of the plate 164, which may conveniently be the anchor pin 173, exerts a knuckling force on the pivotally connected link 163 and wing member 181 tending to yieldably retain the said link and member in relatively vertically aligned positions, a stop lug 189 on the latter member which engages a side of the link serving to establish the said alignment and limiting an extremity of the range through which the link and wing member may be pulled by contractive force of the spring 197. Completing the mechanism is a lever 199 secured to an end of the upper rocker shaft 39, so as to swing in correspondence with rotary movements of the latter, which is provided at the distal end thereof with a roller 201, journaled on a suitable pivot pin 202 carried by the lever, and engageable with the vertically rockable cam face 203 of a downward wing extension 204 of the release lever 91.

Due to the linear speed at which the package sheets 28 and 31 are advanced along the table, it would be mechanically difficult to design a cam 84 which would, at the same time, effect the instant release of the strip-driving sealing rolls 47 necessary to high speed operation and to precisely time the cycles of the shear blade 149, by the elimination of substantial momentum overrun of the strips and their driving elements so that cut-offs would repeatedly be made exactly medially of the longitudinal sides of the transverse areas sealed by the head members 114 and 118. Mounted on a side portion of the table at a distance from the shear blade 149 which is an exact multiple of the width of the desired package which is prescribed by the linear spacing between the imprint marks 37 on the lower package strip 28, is a photoelectric cell unit 206 connected through conductors 207 and suitable current source and amplifying means, as is well known in the art, with the energizing coil of the solenoid 192. A choice in the type of photoelectric mechanism is permissible. As here shown, for purposes of simplicity in the drawings, the photo-electric unit 206 may be positioned overlying the upper surface of the lower package strip 28 with the light transmission aperture or lens 208 vertically superposed over the path traveled by the imprint marks 37, the light beam for energizing the photocell being transmitted upwardly through the translucent package sheet from a suitable exciter lamp contained in the subjacent housing 209, the imprint areas 39, of course being opaque so as to interrupt the light beam. It is also within the scope of the invention, and as is well known in the art, to arrange the photo-electric apparatus so that both the photocell and exciter lamp units are disposed on the same side of the package sheet in which case the imprint areas 39 would be composed of ink or other coating material containing a silvery metallic pigment such as powdered aluminum or the like so as to effect retroverse reflection of the exciter lamp beam into the photocell, the beam being interrupted when the imprint area 39 moves out of registry with the projection path of the beam.

In operation, and starting from a point in the cycle wherein the respective feed, transverse sealing and cut-off mechanisms are at rest it will be seen that the trip mechanism illustrated in Figure 3 will also be at rest, resulting in the flywheel clutch being disengaged to inactivate the camshaft 76. By manual depression of the con-

trol bar 99 as previously explained the sealing rolls 47 will be brought into engagement with the package sheets in instituting the act of advancing the latter along the table and the follower roll 86 will then have been moved to lie in the radially recessed portion of the cam 84. Thus the package sheets gripped by the sealing rolls will be caused to advance along the table. As an advancing imprint area 37 carried by the bottom sheet 10 28 comes into registry with the photo-electric unit light beam the latter will be interrupted, or reflected as the case may be, thereby causing the solenoid 192 to be energized. Such energization of the solenoid causes a rather complex series of 15 actions to occur in the trip mechanism illustrated in Figure 3. The first portion of downward movement of the solenoid armature 191 will cause the lever 176 to start its downward swing and in so doing will effect a downward knuckling of the 20 toggle links 167 and 169, as shown in Figure 3A, by virtue of the interconnection between the lever and toggle links by the interposed link and wing members 183 and 181 respectively. This downward knuckling of the toggle links causes, simultaneously, outward swinging of the release lever 91 so as to effect engagement of the flywheel clutch and interaction of the cam 203 and lever 199 so as to effect an instantaneous release of the sealing rolls 47 from the package sheets, independent of the action controlled by the lever 61, so as to halt advance movement of the latter along the table. Further movement downwardly of the solenoid armature will bring the roller 186 into engagement with the cam surface 187 of 35 the fixed block 188 thereby causing, as shown in Figure 3B, an outward knuckling of the normally vertically aligned link 163 and wing member 181 and effecting an immediate upward swing and realignment of the toggle links 167 and 169 40 which swings the release lever 91 inwardly to its normal rest position to engage and trip the flywheel clutch after the trip finger 89 thereof has made a single revolution. Even though the cam 203 returns with the release lever 91 to an upward position, the latter will not be followed by the lever 199 controlling the separation of the sealing rolls for the reason that in the interim between the cycling movements of the release lever 91, the camshaft 76 has started to rotate 45 and consequently the function of holding the sealing rolls relatively apart will be taken over by the lever 61 and its actuating cam 84. While the sealing rolls are apart, the rotating camshaft 76 will cause cycling movements of the transverse sealing heads 114 and 118 and also of the shear blade 149 to cut off the most advanced completely formed package which has been projected to 50 overlie the discharge opening 13. As the camshaft 76 completes its unit cycle of rotation the follower roller 86 will remain in position radially outwardly of the cam 84 under restraint of the linearly aligned toggle links 169 thereby preventing reengagement of the sealing rolls 47 with the package sheets. At the inception of a successive 55 movement of the package sheets, the imprint area 37 will be moved out of the light beam of the photo-electric unit which will immediately effect deenergization of the solenoid 192 allowing the armature 191 thereof to be moved by the tensioned springs 194 and 197 to its upper limit of travel. During such action, the articulated link 183 and wing member 181 will be restored to their relatively vertically aligned relationship 60 while the lever 176 will freely swing to its normal upward horizontal position without disturbing 65 70 75

the horizontal alignment of the toggle links 161 and 169 which continue to hold the release lever 91 in position to retain the flywheel clutch in released condition. This of course restores the roller 201 to its initial position of engagement with the cam 203 and in readiness for the following cycle of operations when the succeeding imprint 31 of the lower package sheet is brought into registry with and interrupts the photo-electric light beam. From the foregoing description of the operation of the trip mechanism it will be seen that the novel arrangement is provided wherein, in a single unidirectional movement of the solenoid armature 191, the clutch release lever 91 is caused to move through a multi-directional operative cycle only of sufficient duration to effect release of the clutch trip finger. This phase of operation may be completed in the fractional part of a second and thereby renders the packaging mechanism capable of higher operational speeds and consequently greater output capacity than could be achieved with less sensitive or agile mechanism. Also it will be seen that since the operations of strip feed, sealing and cut-off are all synchronized through the mechanical control unit shown in Figure 3, and the photo-electric unit, permanent disparities or occasional variations in the rotational speeds of the separate drive motors 72 and 82 will not upset the overall efficiency and precision of operation of the machine.

We claim:

1. A package forming and sealing machine comprising guide means along which superposed strips of package forming material having interposed therebetween relatively spaced articles to be packaged may be moved along a generally horizontal path, means intermittently engaging said strips adjacent the edges thereof and for moving the latter and said articles in unison and in measured increments along said guide means, said strip moving means including means for sealing together spaced primary areas of said strips extending in the direction of movement thereof, means engageable with said strips and operative between increments of movement thereof for sealing together said strips in relatively spaced transverse areas thereof intermediate the positions of said articles and intersecting said primary areas, and means engageable with said strips and operative between said increments of movement thereof for cutting sections therefrom in said secondary transversely extending sealed areas.

2. A package forming and sealing machine comprising guide means along which superposed strips of package forming material having interposed therebetween relatively spaced articles to be packaged may be moved, means intermittently tractionsly engageable with said strips for moving the latter and said articles along said guide means in measured increments equivalent to the relative spacing between said articles, means carried by said strip moving means and engageable with opposite sides of said strips for sealing together continuous spaced primary areas of said strips and operative between increments of movement thereof for sealing together said strips in spaced transverse secondary areas thereof intermediate the positions of said articles and intersecting said primary sealed areas, means engageable with said strips and operative between said increments of movement thereof for cutting sections therefrom in said secondary transversely extending sealed areas, control means associated

5 10 15 20 25 30 35 40 45 50 55 60 65 70 75

with and for governing operation of said strip moving, sealing and cutting means, and elements carried by one of said strips for actuating said control means.

3. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, a plurality of rotatable drive members arranged to relatively approach and recede from each other so as to respectively engage said strips therebetween so as to move said strips and the articles carried thereby in unison along said table and to release said strips so that said movement along the table will be interrupted, means for rotating said drive members, means for intermittently moving said drive members towards and from each other, means cooperative with said drive members for simultaneously sealing said strips together along opposed marginal edges thereof and during intervals when said strips are being moved along said table, separate sealing and cut-off means intermittently engageable with said strips for respectively effecting sealing together of said strips in transverse areas thereof between said spaced articles and for separating sections of said strips in planes traversing said transverse sealed areas, and means for actuating said sealing and cut-off means during intervals when said drive members are relatively receded with respect to said strips.

4. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, a plurality of rotatable drive members arranged to engage said strips therebetween so as to move said strips and the articles carried thereby in unison along said table, means for rotating said drive members, means for intermittently moving said drive members towards and from each other so as to intermittently engage said strips for movement thereof and to release said strips so that said movement along the table will be interrupted, means cooperative with said drive members for simultaneously sealing said strips together along opposed marginal edges thereof and during intervals when said strips are being moved along said table, separate sealing and cut-off means intermittently engageable with said strips for respectively effecting sealing together of said strips in transverse areas thereof between said spaced articles and for separating sections of said strips in planes traversing said transverse sealed areas, means for actuating said sealing and cut-off means during intervals when said drive members are relatively receded with respect to said strips, and means operative upon movement of a strip along said table for synchronizing the movement of said

strips and the movements of said transverse sealing and cut-off means.

5. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, rotatable drive members disposed on opposite sides of said first and second strips of material and arranged to engage and move said strips therebetween and along said table, means for rotating said drive members, means for intermittently moving said drive members towards and from each other so as to intermittently engage said strips for movement thereof and to disengage said strips to terminate said movement thereof, means associated with said drive members for sealing said strips together along opposed marginal edges thereof, separate sealing and cut-off means intermittently engageable with said strips for respectively effecting sealing together of said strips in transverse areas thereof between said spaced articles and for separating sections of said strips in planes traversing said transverse sealed areas, and means for alternately bringing said sealing and cut-off means into engagement with said strips when said drive members are moved from said strips and for moving said drive members toward and to engage said strips when the sealing and cut-off means are out of engagement with said strips.

6. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, rotatable roll members disposed above and below said strips of material and arranged to engage said strips therebetween so as to move the strips along said table, means for rotating said drive members, means for intermittently moving said drive members towards and from each other so as to intermittently engage said strips for movement thereof and further movable relatively apart so as to disengage said strips and interrupt movement thereof, means in said rolls for sealing said strips together along opposed marginal edges thereof, separate sealing and cut-off members arranged in relatively spaced positions longitudinally of said strips vertically reciprocable to intermittently engage said strips for sealing together transverse areas thereof intermediate said spaced articles and for separating sections of said strips in planes traversing said transverse sealed areas thereof, means for reciprocating said sealing and cut-off members, and means for moving said drive members toward and from each other in displaced phase relationship to reciprocatory movements of said sealing and cut-off members.

7. A package forming and sealing machine comprising a table, a first carrier adjacent an

end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, rocker shafts journaled on and in transverse relation to said table, means connecting said rocker shafts for opposed reciprocatory movement relative to each other, rotatable roll members carried by said rocker shafts disposed above and below said strips to engage the latter therebetween, a drive motor connected with and to constantly rotate said roll members in relative opposite directions, means for intermittently moving said roll members relatively toward and away from said strips so as to intermittently engage said strips for movement thereof and to disengage said strips so that movement will be interrupted, a rotary camshaft journaled on and disposed transversely of said table, a driving motor for said camshaft, clutch means interposed between and for effecting selective engagements and disengagements of said cam-

shaft and said driving motor, separate sealing and cut-off members relatively spaced longitudinally of said table and reciprocably movable toward and from said strips for respectively sealing together transverse areas of said strips intermediate said spaced articles and for separating sections of said strips in planes traversing said transverse sealed areas thereof, means connecting said sealing and cut-off members with and for reciprocatory movement in response to rotation of said camshaft, control means cooperative with said clutch means for alternatively activating and deactivating the latter, means connected with said control means for reciprocably moving said rocker shafts so as to move the roll members to alternately engage and disengage said strips, and spaced elements on one of said strips operative upon movement of the latter along the table for actuating said control means.

8. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, rocker shafts journaled on and in transverse relation to said table, means connecting said rocker shafts for opposed reciprocatory movement relative to each other, rotatable roll members carried by said rocker shafts disposed above and below said strips to engage the latter therebetween, a drive motor connected with and to constantly rotate said roll members in relative opposite directions, means for intermittently moving said roll members relatively toward and away from said strips so as to intermittently engage said strips for movement thereof and to disengage said strips so that movement will be interrupted, a rotary camshaft journaled on and disposed transversely of said table, a driving motor for said camshaft, clutch means interposed between and for effecting selective engagements and disengagements of said cam-

shaft, and said driving motor, separate sealing and cut-off members relatively spaced longitudinally of said table and reciprocably movable toward and from said strips for respectively sealing together transverse areas of said strips intermediate said spaced articles and for separating sections of said strips in planes traversing said transverse sealed areas thereof, means connecting said sealing and cut-off members with and for reciprocatory movement in response to rotation of said camshaft, control means including a solenoid actuating element cooperative with said clutch means for alternately activating and deactivating the latter, means cooperatively connected for movement with said solenoid and with said rocker shafts for reciprocably moving the latter so as to move the roll members to alternately engage and disengage said strips, photoelectric means connected with and to control energizations and deenergizations of said solenoid, and spaced elements on one of said strips operative upon movement of the strips along the table for actuating said photo-electric means.

9. A package forming and sealing machine comprising a table, a first carrier adjacent an end of said table for containing strip material and from which a first strip of material may be dispensed to pass along said table, a second carrier for strip material spaced relatively to said first carrier from which a second strip of material may be dispensed to overlie said first strip, said space between said carriers defining a loading space in which articles to be packaged may be placed in relatively spaced array on said first strip of material, a plurality of rotatable drive members arranged to respectively engage said strips therebetween so as to move said strips and the articles carried thereby in unison along said table, means for rotating said drive members, means for effecting relative movement of said drive members to approach and recede from each other so as to respectively engage said strips for movement of the latter and to release said strips so that said movement along the table will be interrupted, means cooperative with said drive members for simultaneously sealing said strips together along opposed marginal edges thereof

and during intervals when said strips are being moved along said table, separate sealing and cut-off means intermittently engageable with said strips for respectively effecting sealing together of said strips in transverse areas thereof between said spaced articles and for separating sections of said strips in planes traversing said transverse sealed areas, means for actuating said sealing and cut-off means during intervals when said drive members are relatively receded with respect to said strips, control means connected and operative with said drive members and said transverse sealing and cut-off means for synchronizing the movement of said strips and the movements of said transverse sealing and cut-off means, and means carried by one of said strips and operative upon movement of the latter for actuating said control means.

10. The package forming and sealing machine comprising guide means along which superposed strips of package forming material may be moved along a generally horizontal path, means engaging said strips for moving the latter in unison and in measured increments along said guide means, means for sealing together spaced primary areas of said strips extending in the direction of movement thereof, means engageable with said strips and operative between increments of movement thereof for sealing together said strips in relatively spaced transverse areas thereof and intersecting said primary areas, and means engageable with said strips and operative between said increments of movement thereof for cutting sections therefrom in said secondary transversely extending sealed areas.
